THERMOSTATIC CONTROL MEANS

Christian R. Mueller, Highland Park, Mich.

Application December 17, 1936, Serial No. 116,438

1 Claim. (Cl. 297—8)

This invention relates to improved thermostatic control means, the principal object being the provision of structures that are simple in construction, efficient and positive in operation, and economical to produce.

Further objects of the invention include the provision of a novel form of thermostat structure adapted to be controlled by the temperature of the cooling medium for the engine of a motor vehicle; the provision of a thermostat structure adapted to be controlled by the temperature of the cooling fluid of an internal combustion engine and so constructed and arranged as to be quickly responsive to changes in the temperature of the cooling medium without obstructing the flow of the cooling medium through the regularly provided passages therefor; the provision of a thermostatic structure for use in connection with internal combustion engines including a bulb and a water passage for the cooling fluid of the engine, the two being formed as a unit whereby to facilitate the transfer of heat between them; the provision of a thermostat construction for motor vehicles having a fluid cooling system including a bulb and a water passage element, the element being adapted for insertion in the fluid circulating system of the engine and being formed as a unit with the bulb; the provision of a thermostat structure for controlling a motor vehicle part including a bulb the contents of which are in heat conducting relation with respect to the cooling fluid of the engine through a metallic wall, and which is so constructed and arranged as to permit filling of the bulb at atmospheric pressure, the filling of which bulb is relatively insensitive to variation of filling liquid therein, and in which the filling fluid may be any one of relatively cheap and commonly known liquids such as ethyl or methyl alcohol or gasoline; the provision of a thermostat structure adapted for insertion in the hose connecting the cooling jacket of an internal combustion engine with its cooperating radiator, and in which rapid transfer of heat between the cooling medium and the contents of the bulb is provided for without restricting the flow of the cooling medium through the hose; and the provision of a thermostat structure for motor vehicles and the like having an internal combustion engine and a cooling radiator including a thermostatic bulb and means cooperating therewith adapted for insertion in the usual hose connecting the cooling jacket of the engine with the radiator and so constructed and arranged as to be substantially

immediately effective to temperature changes in the cooling fluid passing through the hose.

The above being among the objects of the present invention the same consists in certain novel features of construction and combinations of parts to be hereinafter described with reference to the accompanying drawing, and then claimed, having the above and other objects in view.

10 In the drawing which illustrates suitable embodiments of the present invention and in which like numerals refer to like parts throughout the several different views,

15 Fig. 1 is a partially broken sectional view taken centrally through a preferred form of expandible bellows structure preferably employed in the thermostatic control of automobile radiator shutters according to the present invention;

20 Fig. 2 is a sectional view taken centrally through the thermostatic control bulb and associated cooling passage of the thermostat construction employed for controlling the operation of the bellows shown in the preceding view; and

25 Figs. 3 and 4 are views similar to Fig. 2 but showing modified forms of construction.

30 In accordance with conventional practice radiator shutters have been thermostatically controlled either by the employment of a thermostatic element positioned in the path of flow of air passing through the cooperating radiator or else have been placed directly in the radiator header. In the former practice the transfer of heat between the cooling medium for the engine and the thermostat is so slow that a considerable lag in the operation of the shutter results with consequent disadvantages and in the latter practice it requires special construction of the radiator header, introduces complications into the construction of the same and is liable to leakage about the line of junction between the thermostatic element and the radiator header. In accordance with the present invention the thermostatic element for operating the radiator shutters is so constructed and arranged as to permit it to be quickly and easily inserted in any existing structure and without requiring any changes other than simply cutting a section out of the usual hose connecting the cooling jacket of the engine with the radiator. At the same time the construction is such that the thermostatic element is immediately responsive to any changes in temperature of the cooling medium flowing through such hose. Additionally the construction of the thermostatic portion of the device is such as to permit it to use cheap and common

liquid as either ethyl or methyl alcohol or gasoline as the actuating fluid in the thermostat and does not require accurate or a predetermined degree of filling to thereafter insure the proper and satisfactory operation of the device.

According to the present invention a novel form of thermostatic means is employed which is particularly adapted for controlling the operation of the shutters. Broadly this thermostatic means comprises a bellows unit indicated generally as at 104, a bulb unit indicated generally at 106, and a tube 108 inter-connecting the bellows unit and bulb unit. The bellows unit 104 is preferably rigidly secured to the frame 26 and includes an axially movable rod 110 adapted to be suitably connected to the bar 94 to actuate the same against the force of the spring 102. The form of connection between the rod 110 and the bar 94 may be of any suitable construction and will depend to some extent upon the position in which the bellows assembly 104 is secured to the frame 26, the latter position being governed primarily by the available space for it and the matter of convenience.

The bellows assembly 104 may be suitably secured to a suitable frame portion of the vehicle with the rod 110 thereof projecting downwardly therefrom. It is to be understood that the rod 110 is connected to the shutters through suitable operating mechanism so that the shutters are pivoted about their axes upon expansion and contraction of the bellows.

Referring now to Fig. 1 it will be noted that the bellows assembly 104 comprises a housing 120 having removable ends 122 and 124, respectively. Positioned within the housing 120 and suitably fixed to the end 124 is a metal bellows 126. The free end of the bellows 126 is provided with a stem 128 suitably guided for axial movement in a sleeve 130 fixed in the end wall 122. The rod 110 is suitably secured to the stem 128 as by threading or the like so as to receive from the stem 128 equal axial movement therewith. A connection 132 communicating with the interior of the bellows 126 projects through the wall 124 and on the upper side of the wall 124 is provided with a nut 134 serving to removably clamp it to the wall 124. The tube 108 is connected to the connection 132 in any suitable manner such for instance as by means of a conventional type of compression coupling.

Referring now to Fig. 2 the bulb assembly 106 comprises a hollow container 140 provided with a removable plug 142 in its upper end wall and at its lower end provided with a connection 144 communicating the interior of the tube 108 to the interior of the container 140. It will be understood that in practice the interior of the bellows 126, tube 108 and container 140 is filled or substantially filled with a suitable expandable or vaporizable liquid. It is not essential, however, that the entire available volume of these parts be completely filled with such fluid and in fact it has been found preferable to leave a small amount of air such as indicated at 146 in Fig. 2 above the level of the fluid 148 in the bulb for the purpose of effecting actuation of the bellows 126.

As will be understood by those skilled in the art the fluid 148 in the bulb assembly 106 is adapted to be positioned in heat transferring relation with respect to the cooling fluid for the internal combustion engine to which the shutter mechanism is adapted, and when the temperature of such cooling fluid reaches a predetermined

high limit the expansion or partial vaporization of the fluid 148 will set up a pressure within the thermostatic system which will cause expansion of the bellows 126 and movement of the rod 110 and consequent opening of the shutter mechanism against the force of a spring to permit the temperature of the cooling fluid to be reduced. When the pressure in the thermostatic system is reduced through cooling of the fluid medium the pressure of a spring will cause the shutter to be closed a corresponding amount.

As previously explained it has been conventional practice to either position the thermostatic element for a radiator shutter in the path of flow of air passing through the radiator, in which case the action of the radiator shutter is relatively sluggish and lags behind the changes in temperature of the cooling fluid, or to position the thermostatic element directly in the header 20 of the cooling radiator in which case the radiator must be especially constructed to receive it and renders the radiator liable to leaks. In either case the heat exchange between the cooling medium for the engine and the thermostat must 25 usually take place through a body of air which in and of itself being a relatively good heat insulator, detracts from the speed of operation of the device.

This disadvantage of conventional constructions is eliminated in accordance with the present invention by providing for the transfer of heat between the cooling medium and the fluid 148 in the bulb assembly 106 through highly heat conducting metal walls rather than through air, 30 and so constructing the device that this may be accomplished without any special construction of the cooling system for the engine and permitting the application of the present invention to any existing engine structure in a quick and efficient 35 way which will not obstruct the free flow of cooling medium through the engine cooling system. Specifically this is accomplished in the construction shown in Fig. 2 by providing a sleeve 150 integrally formed or at least directly but metallically connected to the container 140 but laterally spaced therefrom. In Fig. 2 the sleeve 150 is shown as being cast integrally with the container 140 and as being connected thereto through an integral arm 152. The sleeve 150 is of such dimension as to be insertable in the usual hose 154 conventionally employed in motor vehicles to connect the outlet from the cooling jacket of the engine 155 with the cooling radiator upper header. To insert the sleeve 150 thereinto all that is 40 necessary is to cut the hose 154 at the desired point and then insert the opposite ends of the sleeve 150 into the adjacent ends of the hose 154 provided by such cutting. Conventional clamps 45 156 are preferably provided for insuring a watertight connection between the hose 154 and the sleeve 150.

The bulb assembly 106 whether formed integrally as shown in Fig. 2 or of separate parts rigidly secured together into a unitary structure, 50 is preferably formed of metal having a high rate of heat conductivity such for instance as aluminum, magnesium, copper, brass or the like so that a quick and direct path of heat transfer will be provided between the water flowing 55 through the hose 154 and the fluid content 148 of the container 140. In this respect it will be noted that the sleeve 150 serves as heat conducting fins on the arm or neck 152 and materially aids in the rapid transfer of heat between the container 140 and its contents and the water

flowing through the hose 154. It has been found that the transfer of heat through a construction substantially identical to that shown in Fig. 2 and formed of aluminum is so rapid and causes the fluid content 148 of the container 140 to respond so quickly to variations in change of the temperature of the water flowing through the hose 154 that when operating a radiator shutter of the type previously described it is capable of maintaining the temperature of the cooling water for the engine within a plus or minus 3° F. of the desired temperature over a wide variation of engine speeds and loads.

As has been previously mentioned the fluid content 148 of the container 140 and also the tube 108 and bellows 126 may be one of such common liquids such as methyl or ethyl alcohol or gasoline. When filled with ethyl alcohol the radiator shutter will be operated to hold the temperature of the cooling water of the engine at substantially 170° F. Methyl alcohol when employed will hold the temperature of the cooling water at substantially 160° F. and first grade gasoline at 150° F. Other temperatures can, of course, be maintained by employing one or more other suitable liquids or combination of liquids and the operation of the shutter may also be effected to some extent by changing the tension of the spring 102. The container 140 and its connected tube 108 and bellows 126 may be filled at atmospheric temperature and at atmospheric pressure with any of the above described liquids and as previously described the degree of filling of the container 140 is more or less unimportant as long as there is a material amount of the liquid 148 therein. It will, of course, be understood that the container 140 may be positioned in any suitable or convenient relation with respect to the sleeve 150 but in any event it will be advisable that the actual point of connection of the tube 108 with the interior of the container 140 is adjacent the bottom of the container.

In Fig. 3 a modification of the construction shown in Fig. 2 is illustrated. In this modification the bulb assembly 106' is formed from sheet metal and the construction is further modified to provide for the direct circulation of the cooling fluid for the engine flowing through the hose 154' directly around the container 140' for the thermostatic fluid 148'. In this case the container 140' has a mean body portion 160 formed from a length of metal tubing and an upper and lower head 162 and 164 respectively suitably secured and sealed to the main body portion 160. A removable filler plug 142' is provided in the upper head 162 and corresponds to the plug 142 in the construction shown in Fig. 2. In this modification instead of connecting the tube 108, corresponding to the tube 108 in Fig. 2, into the side of the container it is connected into the container through the bottom wall 164 by means of a suitable fitting 144'. In order to connect the container 140' with the sleeve portion of the device a pair of sheet metal stampings 166 and 168 are provided. These stampings 166 and 168 are provided with inturned marginal flanges which nest within each other to space the main body portions of the members 166 and 168 from each other so as to form a hollow structure. Each of the stampings 166 and 168 adjacent but spaced from one end thereof is provided with an outwardly turned flange 170 of a size and shape to closely receive the main body portion 160 of the container 140' therein. Similar flanges 172 are

provided adjacent the opposite end of the stampings 166 and 168 and each of the flanges 172 receive therein a short length of tubing 174, the length of tubing 174 cooperating with the corresponding flanges 172 to provide a sleeve structure, such as the structure 150 previously described, for reception in the hose 154'. The joints between the various parts of the mechanism thus described are, of course, carefully soldered or otherwise sealed so as to render them tight against leakage.

It will be understood that with the construction shown in Fig. 3 a passage is provided between the members 166 and 168 which extends 15 completely around the container 140' and is in open communication with the interior of the hose 154' so that when the engine cooling fluid is flowing through the hose 154' it will have more or less of a tendency to circulate directly around 20 the container 140' so as to effect a rapid transfer of heat between the fluid 148' in the container 140' and the engine cooling fluid.

Should it be desired to provide a positive circulation of the engine cooling fluid flowing 25 through the hose 154' through the passage formed between the members 166 and 168 and around the container 140', when the members 166 and 168 are assembled a dividing wall member 180 may be inserted between them. The member 180 may have marginal ears such as 182 struck in opposite directions therefrom to maintain it centrally of the passage between the members 166 and 168 and if desired it may be formed to encircle the container 140' so that 30 even though it may be more or less loose in its position it is held against material displacement. The member 180 may have a lip 184 thereon projecting into intersecting relation with respect to the stream of cooling fluid flowing 35 through the sleeve portion of the device and inclined towards the direction from which the flow is received so as to deflect a portion of such flow inwardly through the passage between the members 166 and 168 around the container 140' and then up over the wall 180 and back into 40 the main flow stream through the hose 154'. In this manner a positive circulation of the cooling fluid flowing through the hose 154' directly against the container 140' is assured and consequently any tendency of the thermostatic means to lag behind changes of temperature in the cooling fluid of the engine is effectively and 45 efficiently eliminated.

In Fig. 4 a construction similar to that shown 50 in Fig. 3 is illustrated but embodies certain modifications not shown in either Fig. 2 or Fig. 3. In this case the container 140'' is constructed in the same manner as the container 140' in Fig. 3 with the exception that the lower wall 164' is imperforate and the tube 108'' is introduced 55 through the top wall 162' of the container 140'', but in order to insure flow of liquid into the tube 108'' from the bottom of the container the tube 108'' is provided with an extension 186 within 60 the container 140'' which extends downwardly through the container to a point adjacent the lower wall 154' thereof. In this case members 166' and 168' corresponding to the members 166 and 168 in Fig. 3 are provided and are secured 65 to the container 140'' in a similar manner except that the flanges 170' are formed at one end of the members for reception of the container 140'' instead of spaced from such ends as in the construction shown in Fig. 3. Additionally the wall 70 of the container 140'' is cut away as at 188 to 75

provide free communication between the interior of the container 140' and the space between the members 166' and 168'. Also instead of using the short length of tubing such as the parts 174 in Fig. 3, a single length of tubing 190 is projected through both flanges 172' to form the sleeve portion of the device and consequently the piece of tubing 190 seals the flow of fluid through the hose 154' from the space between the members 166' and 168'. It will be observed that in this construction the thermostatic fluid 148' not only fills the interior of the container 140' but also the space between the members 166' and 168' and consequently surrounds the sleeve 190 through which the cooling fluid for the engine flows. The result of this construction is, of course, substantially equivalent to that shown in Fig. 3.

Formal changes may be made in the specific embodiment of the invention described without departing from the spirit or substance of the broad invention, the scope of which is commensurate with the appended claim.

What I claim is:

A thermostatic control means responsive to the temperature of a fluid flowing through a hose of a cooling system comprising a bellows, a thermostatic bulb arranged in adjacent relationship to said hose and operatively connected to said bellows, and a volatile fluid in said bellows and bulb, the combination of a metallic sleeve of relatively axially extended length inserted in said hose between adjacent ends of adjacent sections thereof forming means for clamping said ends in fluid-tight relation to each other and with the interior surface of said sleeve exposed to the direct flow of water therethrough, an arm connected with said sleeve in intimate heat exchange relationship therewith intermediate the ends thereof projecting laterally therefrom and connected to said bulb in intimate heat exchange relationship therewith, said arm being of substantial cross-sectional configuration whereby to effect a rapid transfer of heat between said water in said hose and said volatile fluid in said bulb.

CHRISTIAN R. MUELLER.
